UNITED STATES PATENT OFFICE.

WILLIAM L. LENTZ, OF TUCKAHOE, NEW YORK.

LOCOMOTIVE SMOKE BOX.

Application filed April 13, 1927. Serial No. 183,376.

My invention relates to locomotives, and has for its object the provision of an improved type of smoke-box construction adapted to accommodate the piping forming a part of one or more of the locomotive auxiliaries.

One of the locations frequently used for locomotive feed water heaters is above the forward portion of the locomotive smoke-box, ahead of the stack, and with a feed water heater so located it is necessary to make numerous steam and water connections between the lower portions of the locomotive and the heater.

15 The location and arrangement of the necessary connecting pipes is a matter of considerable difficulty, as the permissible clearances in modern locomotives are so small that there is frequently insufficient 20 room for the larger pipes to be brought up to the heater outside the locomotive boiler, and such piping even though it can be arranged in this manner forms a serious obstruction to the view of the locomotive engineer.

In order to remedy this undesirable condition, it has been proposed to indent the sides of the smoke-box walls to form a depressed channel for the reception of such 30 piping, and the present invention is in the nature of an improvement on this construction, by means of which the necessary piping may be carried through the interior of the smoke-box.

35 In modern locomotive boilers, the diameter of the boiler shell and that of the smoke-box is very large, and my invention further contemplates the provision of a structure which will provide a desirable stiffening of the 40 sheets forming the smoke-box walls.

I have illustrated my invention in the accompanying drawings in which Fig. 1 is an elevation of the forward portion of the locomotive; Fig. 2 is a transverse elevation 45 partly in section of the locomotive; and Fig. 3 is a fragmentary section taken on the line 3—3 of Fig. 2 and showing the detailed construction.

Referring now to Fig. 1, 1 indicates the 50 sheet forming the walls of the smoke-box in which is located the stack 2 and which is provided with a flattened top 3 upon which is mounted the feed water heater 4. For 55 illustrative purposes I have shown the smoke-box walls formed by a single integral sheet, but obviously such sheet may be built

up of a number of arcuate sections, and as hereinafter used in the claims the term "sheet" is to be understood as including all such equivalent forms of construction. The 60 heater illustrated is of a known type receiving exhaust steam from the engine valve chests 5 through the exhaust steam supply pipes 6 and discharging the condensate therefrom through the condensate line 7. Boiler 65 feed water is supplied from the usual feed pump 8 through conduit 9 to the heater, from which it passes through conduit 10 and check valve 11 to the locomotive boiler.

The location of the heater and the piping 70 to and away from it is in accordance with well-known practice, but by my invention I provide an improved means for taking care of the exhaust steam conduits 6 and such other conduits as it may be desirable to pass 75 through the smoke-box. I accomplish this by providing at either side of the smoke-box the vertical tubular members 12 and 13 which connect suitable openings 14 near the bottom of the smoke-box with corresponding 80 openings 15 in the top 3. The members 12 and 13 are permanently secured to the walls of the smoke-box sheet around the openings therein, preferably by welding, so that an air-tight joint is secured between these members 85 and the walls of the smoke-box.

It will be apparent from an inspection of Fig. 2 that the members 12 and 13 form not only passages suitable for the reception of piping, but also form vertical stiffening 90 members which aid materially in distributing the weight of the heater more uniformly over the smoke-box walls.

The members 12 and 13 may be of any desired cross-sectional form, but I prefer to 95 form such members either of circular or elliptical tubing, the sectional form employed depending upon the number and size of the pipes which are to be run through them. For illustrative purposes I have 100 shown in Figs. 2 and 3 the member 12 of nearly circular form and have shown as located therein only a single exhaust steam pipe 6, while the member 13 is more decidedly elliptical in form in order to accommodate 105 not only an exhaust pipe 6 but the condensate return pipe 7.

Obviously, the number or character of the pipes located in the tubular members 12 and 13 are immaterial to the present invention, and it will also be readily apparent 110 that the smoke-box need not necessarily be

provided with a flat top sheet such as I have shown, but may be in the form of a full cylinder with the members 12 and 13 attached to the smoke-box walls in the same manner at both their upper and lower ends.

Many changes and modifications in the form illustrated will suggest themselves to those skilled in the art, but all such changes and modifications as may fall within the scope of the appended claims are to be understood as within the scope of the invention.

I claim:

1. In a locomotive, a sheet forming a smoke-box wall and having a pair of openings therein, one of said openings being in the lower portion of said sheet and the other of said openings being in the upper portion of said sheet, and a tubular member permanently secured to said sheet around said openings and passing through the smoke-box.

2. In a locomotive, a sheet forming a smoke-box wall and having a pair of upper and lower openings on each side of the smoke-box, and tubular members connecting each pair of openings and passing through the smoke-box.

3. In a locomotive, a sheet forming a smoke-box wall and having a pair of verti-

cally aligned upper and lower openings on each side of said smoke-box, and a pair of vertically disposed tubular members passing through the smoke-box and connecting each of said pairs of openings, said members forming vertical weight bearing stiffeners providing open passages through the smoke-box.

4. In a locomotive, a smoke-box forming sheet having an arcuate lower portion and a plane upper portion, said sheet being provided with an opening in its upper plane portion and a corresponding opening in its lower arcuate portion, and a tubular member connecting said openings.

5. In a locomotive a smoke-box forming sheet having an arcuate lower portion and a horizontal plane upper portion, said sheet having openings in its plane portion at each side of the smoke-box and corresponding openings in the lower arcuate portion, said lower openings being vertically aligned with said upper openings, and a pair of tubular members passing through said smoke-box with each of said members connecting one of said upper openings with one of said lower openings.

WILLIAM L. LENTZ.
